(57) CLAIM

The ornamental design for an automobile, as shown and described.

DESCRIPTION

FIG. 1 is a rear perspective view of an automobile showing my new design;

FIG. 2 is a front view thereof; and

FIG. 3 is a rear view thereof; and,

FIG. 4 is a side view thereof.

The broken lines in the drawings illustrate portions of the automobile that form no part of the claimed design.

1 Claim, 4 Drawing Sheets

FIG. 1

FIG. 4
